UNITED STATES PATENT OFFICE.

ROBERT L. YEAKEY, OF CAVE IN ROCK, ILLINOIS.

DESIGN FOR A VIOLIN.

50,048.

Specification for Design. Patented Dec. 12, 1916.

Application filed September 22, 1916. Serial No. 121,683. Term of patent 14 years.

To all whom it may concern:

Be it known that I, ROBERT L. YEAKEY, a citizen of the United States, residing at Cave in Rock, in the county of Hardin and State of Illinois, have invented a new, original, and ornamental Design for Violins, of which the following is a specification, reference being had to the accompanying drawings, forming part hereof.

Figure 1 is a side elevation of a violin,

showing my new design. Fig. 2 is a plan view.

I claim:—

The ornamental design for a violin, as shown.

ROBERT L. YEAKEY.
